UNITED STATES PATENT OFFICE.

WILBUR W. WALKER, OF HANFORD, CALIFORNIA.

TIMING AND IGNITION DEVICE.

1,142,212.

Specification of Letters Patent. Patented June 8, 1915.

Application filed January 16, 1914. Serial No. 812,520.

To all whom it may concern:

Be it known that I, WILBUR W. WALKER, citizen of the United States, residing at Hanford, in the county of Kings and State of California, have invented certain new and useful Improvements in Timing and Ignition Devices, of which the following is a specification.

This invention relates to explosive engines, and consists of improved electric sparking mechanism, and controlling mechanism therefor whereby the parts of the said sparking mechanism, may be readily and easily adjusted to regulate or control the time of the spark production.

The object of the invention is to provide an ignition device, the actuation of which is entirely dependent upon the rotation of the crank shaft of the engine.

A further object of the invention contemplates the provision of means in the nature of an auxiliary contact capable of both vertical and longitudinal adjustment to provide, in the first instance for the regulation or control of the time of spark production, and in the second instance, for the final adjustment of the said contacting element for a purpose to be hereinafter fully disclosed.

The above and additional objects are accomplished by such means as are illustrated in their preferred embodiment in the accompanying drawings, described in the following specification and then more particularly pointed out in the claims which are appended hereto and form a part of this application.

In describing my invention in detail reference will be had to the accompanying drawings wherein like characters denote like or corresponding parts throughout the several views, and in which:

Figure 1 is an end view of a portion of an explosive engine illustrating the application of the invention thereto; Fig. 2 is a side elevation of the device as is illustrated in Fig. 1; Fig. 3 is an enlarged longitudinal sectional view of the device; Fig. 4 is a section on the line 4—4 of Fig. 3; and Fig. 5 is a section on the line 5—5 of Fig. 3.

Referring now to the drawings by numeral, 1 designates, as an entirety, the explosive engine, and 2 an auxiliary shaft driven by the crank shaft (not shown) of the engine. Mounted upon one end of the shaft 2 and rotatable therewith, I provide an eccentric 3 from one of the lateral faces

of which a spindle 4 projects. An arm 5 is mounted upon the spindle 4, the movement of the latter according to the rotation of the eccentric 3 adapted to impart a reciprocatory movement thereto. The said arm 5, terminates in a head portion or enlargement 6, one face or edge of which is beveled as at 7 and disposed for engagement with a roller 8 projecting from one end of the engine cylinder, the opposite edge of the said enlargement being slightly curved as at 9 to conform to the configuration of a vertically and longitudinally adjustable contact member 10. The upper or exposed face of the said contact 10 is disposed in the path of an arm 11 oscillatable from a point 12, the oscillatory movement of the said arm 11 being derived by reason of its engagement with the said contact, the latter being reciprocatory with the said arm 5. Mounted upon the engine cylinder in any suitable manner and operated by movement of the arm 11, is an ignition device designated 13 comprising the usual stationary and pivoted contacts (not shown), the former of which is connected to and movable with the said arm.

To provide for the proper adjustment of the contact member 10 means including a movable carriage 14 have been devised, the same, in its preferred embodiment, comprising a casing 15 through an opening 16 of which the said contact member 10 extends. Within the casing the said contact is fulcrumed as at 17, an adjustable thumb screw 18 being disposed for engagement with the inner end thereof. A nut 19 is carried by the thumb screw 18 to lock the same against accidental displacement after proper adjustment has been effected. The said nut 19 also serves as a securing means for a leaf spring 20 the free end of which is adapted for engagement with the contact 10 at a point adjacent its free end, the tension of the said spring normally exerting sufficient pressure upon the said member to maintain its inner end in engagement with the thumb screw 18. The carriage 14 is longitudinally grooved or bifurcated as at 21 to provide for the reception of the arm 5 upon which the said carriage is movable, bolts or screws 22 serving as retaining elements therefor.

Detachably yet rigidly secured to the arm 5, I provide a two-part bracket 23, between the parts or sections of which the said arm 5 extends, bolts 24 being provided to lock

the said parts or sections together. Extending transversely of the bracket 23 and in a plane parallel with the longitudinal axis of the arm 5, is a longitudinally adjustable thumb screw 25, the knob 26 of which is serrated for a purpose to be hereinafter fully described. The inner end of the thumb screw 25 is rigid with the carriage 14, the attachment thereto being effected through the medium of an extension 27 having collars 28 disposed respectively upon the inner and outer faces of the casing 15, a cotterpin 29 extending transversely of the extension 27 and engaging the inner of the collars 28 serving as a lock whereby the carriage 14 is rendered immoveable other than by adjustment effected by manipulation of the thumb screw 25.

The upper end of the bracket 23 is grooved as at 30 to provide for the reception of a lever 31 fulcrumed as at 32 within the said groove, one end of the lever being adapted for engagement with the serrations of the knob 26 to render the latter incapable of turning under normal conditions. To maintain the said lever at all times in engagement with the said knob, a spring 33 is provided and disposed within a recess 34 of the said bracket to abut at one end the lever 31 and at its opposite end the seat of the said recess, this arrangement of the said spring causing the same to at all times exert an upward pressure upon one end of the lever 31 and consequently a downward pressure upon the opposite end thereof. To facilitate the operation of the lever 31, a cap 34' is provided and formed integrally with the said lever at a point directly over that engaged by the spring 33, from which it will be seen that a depression of the said spring may be readily effected.

The construction of the device having been fully described, it now remains to set forth in detail the operation thereof. When it is desired that the time of spark production or ignition be regulated to time more accurately the explosion of the engine charge, the contact member 10 is adjusted, first by the manipulation of the thumb screw 18, and finally and more accurately, by the manipulation of the thumb screw 25. In the first instance, by reason of the engagement between the said thumb screw 18 and the contact 10, the latter is moved upon its fulcrum 17 to raise one end thereof slightly out of engagement with the curved edge of the enlarged portion 6 of the reciprocating arm. By the raising of the contact 10, it is apparent that the stroke of the oscillatory arm 11 commences in advance of what would otherwise be the case. By reason of the engagement between the said arm 11 and the said contact 10, it is apparent that the former is oscillated to in 65 turn actuate the pivoted electrode or con-

tact (not shown) common to ignition devices, thereby causing the said electrode to engage the stationary electrode, the disengagement of which, by reason of the return stroke of the arm 5 and contact 10, will provide for the ignition of the engine charge. Should the adjustment of the thumb screw 18 prove inaccurate, and to provide for final adjustment of the said contact 10, as well as to provide for the application of the device to engines wherein the auxiliary shaft 2 is spaced from the ignition device 13 a greater distance than that disclosed in the drawings, the thumb screw 25 is manipulated, the locking lever 31 being first disengaged from the serrations of the knob 26 thereof. The turning of the screw 25 will longitudinally adjust the carriage 14 upon the arm 5 and move the contact 10 with which it is bodily movable, into the desired position to regulate the timing or control of the ignition device.

It is apparent from the above, taken in connection with the accompanying drawings, that the contact 10 may be extended a considerable distance beyond the enlargement 6 of the arm 5 by the adjustment or manipulation of the thumb screw 25; that the roller 8 serves not only as a support for the said arm but as a bearing for the beveled edge of the head 6 to facilitate in the reciprocatory movement of the said arm; and that accidental movement of either thumb screw 18 or 25 is rendered impossible by reason of, first, the lock nut 19, and second the lever 31.

In reduction to practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion and arrangement of parts may be resorted to, when required, without sacrificing any of the advantages of my invention, as defined in the appended claims.

Having thus fully described my invention, what I claim as new and desire to secure by Letters Patent, is:—

1. In combination with the ignition device of an explosive engine, a member movable through operation of the engine crank shaft, a contact element movable bodily into and out of engaging proximity with said device, means to move said element relatively to said member, said member acting as a support therefor, and means locking said element in its various adjusted positions.

2. In combination with the ignition device of an internal combustion engine, a contact element engageable with the said device, support means for the said element, means

actuatable to bodily move the said support means for adjusting the element relatively to the said device, means actuatable to adjust the element independently of its support means, a spring actuated fulcrum lever engageable with the said first mentioned adjusting means for automatically locking the said support means in its adjusted position, and means actuatable to lock the last mentioned adjusting means in its adjusted position, as and for the purpose set forth.

3. In combination with the ignition device of an internal combustion engine, a member reciprocable through movement of the engine crank shaft, a carriage mounted on said member, a bracket stationary relatively to the member, means movable relatively to the bracket for adjusting the carriage longitudinally upon the member, means operating automatically to lock the adjusting means in its adjusted position, a contact element fulcrumed to and bodily movable with the carriage, and means operating to adjust the element relatively to the carriage, said element being engageable with the said device for controlling ignition, as and for the purpose set forth.

4. In combination with an ignition device for explosive engines, an arm oscillatable upon said device, a reciprocatory arm actuatable through movement of the engine crank shaft, a roller carried by the engine and engageable with said reciprocatory arm to support the latter in operative position, a carriage adjustable longitudi-

nally upon said reciprocatory arm, a contact movable bodily with said carriage, said contact being adapted for engagement with said oscillatory arm, the movement of said contact during reciprocation of said arm adapted to oscillate said first mentioned arm, means carried by said carriage and disposed for engagement with said contact to provide for vertical adjustment thereof, a bracket rigid with said reciprocatory arm, means carried by said bracket and disposed for engagement with said carriage to longitudinally adjust the latter upon said arm, and means including a lever fulcrumed to said lever and engageable with said last mentioned means to maintain the same incapable of actuation, as and for the purpose set forth.

5. In combination with the igniting device of an explosive engine, a member movable through operation of the engine crank shaft, a contact element movable relatively to said member, said member being at all times in engagement with said contact element to brace the latter at its point of contact, means to bodily move said element toward and from said device, and means to lock the element in its various adjusted positions.

In testimony whereof I affix my signature in presence of two witnesses.

WILBUR W. WALKER.
